GOLF CLUB CART

William B. Clarke, Sewickley, Pa.

Application January 18, 1952, Serial No. 18,112

Term of patent 7 years

(Cl. D14—3)

To all whom it may concern:

Be it known that I, William B. Clarke, a citizen of the United States of America, residing in the Borough of Sewickley, county of Allegheny, and Commonwealth of Pennsylvania, have invented a new, original, and ornamental Design for Golf Club Cart, of which the following is a specification, reference being had to the accompanying drawing, forming part thereof, wherein:

Fig. 1 is a side perspective view of a golf club cart showing my new design;
Fig. 2 is a front perspective view;
Fig. 3 is a side view, and
Fig. 4 is an enlarged fragmentary perspective view.

The golf clubs shown in dot-dash lines are for illustrative purposes only.

I claim:

The ornamental design for a golf club cart, substantially as shown and described.

WILLIAM B. CLARKE.
